UNITED STATES PATENT OFFICE.

ALVIN C. McCORD AND IVAR A. RANDEL, OF CHICAGO, ILLINOIS, ASSIGNORS TO
McCORD AND COMPANY, OF CHICAGO, ILLINOIS, A CORPORATION OF NEW
JERSEY.

JOURNAL-BOX CELLAR.

1,189,712.

Specification of Letters Patent.

Patented July 4, 1916.

Application filed April 14, 1916. Serial No. 91,235.

To all whom it may concern:

Be it known that we, ALVIN C. McCORD and IVAR A. RANDEL, citizens of the United States, residing at Chicago, in the county of Cook and State of Illinois, have invented certain new and useful Improvements in Journal-Box Cellars; and we do hereby declare the following to be a full, clear, and exact description of the invention, such as will enable others skilled in the art to which it appertains to make and use the same.

Our invention relates to journal boxes for car trucks, and consists of the novel features hereinafter described and defined in the claims.

Our invention was primarily intended to afford an improved cellar in that type of journal boxes disclosed and claimed, together with the process for manufacturing the same, in the three prior patents to Ivar A. Randel, towit: 1,077,159, of date October 28, 1913, entitled "Journal box;" 1,089,585, of date March 10, 1914, entitled "Process of making journal boxes;" and 1,090,085, of date March 10, 1914, entitled "Journal box."

By reference to said patents, it will be seen that the box therein disclosed and claimed, is an all steel box, wherein the cellar is first independently made from a comparatively thin sheet of steel by the application of suitable dies, and is then placed in a mold and the top is cast fast thereto. The mass of the metal is in the top, and the cellar is of comparatively thin section and light weight.

There are also other boxes, wherein the chief mass of metal is in the top, where it is needed to withstand the normal strains of the service, and wherein the cellar is of comparatively thin section and light weight. In some instances, the cellars and tops are separately made and riveted together, in other instances, the tops and cellars are integral castings annealed, or in other words, the ordinary malleable iron boxes, with extra light cellars. However, these light weight cellars may be formed, the chief strain, which they must withstand, is the one to which they are subjected from the load, when the hoisting jack is applied thereto, to

lift the box and the load for inspection and repairs; and in the case of boxes intended for use on the arch bar type of car truck, the hoisting jack is usually applied to that part of the box outward of the tie bar seat.

Modern freight cars are of large capacity,

usually 80,000 or 100,000 pounds, and the trend is toward still larger capacity.

The primary function of the cellar of a journal box is simply that of a container for the oil and waste; and, if it were not for this necessity of having the cellar of the requisite strength to permit the said usage of the hoisting jack, the cellar might be extremely thin and light. Because, however, of its large load, which must be lifted by the jack, it has been found a serious problem to get the requisite strength where needed, without a large increase in the weight. By our invention, we solve that problem.

In the accompanying drawings, the preferred form of our invention is illustrated as applied to the all steel box of the type disclosed and claimed in said Randel patents; and, in said drawings, like notations refer to like parts throughout the several views.

Figure 1 is a side elevation of said box, with the lid removed; Fig. 2 is a bottom plan of the same; Fig. 3 is a vertical cross section on the line $x^3 x^3$ of Fig. 1; and Fig. 4 is a front end elevation of the box, shown in Figs. 1 and 2, with a portion broken away.

The numeral 1 represents the cellar of pressed steel and the numeral 2 the top of cast steel cast fast thereto. The top 2 is provided with an arch bar seat 3 and journal bolt lugs 4, as in the box of the said Randel patents. The bottom of the cellar 1 is rounded, or of arch-shape in cross section, as best shown in Figs. 2 and 3, at all portions thereof, with the exception of that part lying in the central zone, directly under the arch bar seat 3. At this central zone, the side joining portions, between the adjacent curved parts of the bottom are angularly depressed to get, on the bottom, a flat seat 5 for the tie bar of the truck frame. The bottom of the cellar 1 is also curved, or made of arch-shape longitudinally in that part of its forward end, below the lid opening 6 of the box, as clearly shown in Figs. 1, 2 and 4. The side walls and the front end and bottom walls of the cellar join together, without any sharp corners; or, otherwise stated, the front end corners e extend outward and upward on curved lines, until they merge with the side and the end walls of the box, directly under the lower lip d of the mouth of the box,

at the opposite ends of this lip. This mouth-lip *d*, to wit: that portion of the front wall of the box, directly below the lid opening, is a cross beam connecting the said corners *e* of the box and, for a certain distance below the lid opening, this portion of the front wall is nearly, but not quite vertical, flaring slightly outward, in respect to the curved part of the lower forward end of the box, as best shown in Fig. 1, and standing at an obtuse angle to the side walls of said mouth opening *d*. Hence, this cross beam, afforded by said mouth-lip *d*, is of considerable strength, and, in coöperation with the other peculiar features of the front end of the box, hitherto identified, makes the front end of the box relatively strong, as compared with the vertical side walls of the cellar. To get the further needed strength, for jacking purposes, we provide a depressed boss *a* in that part of the bottom of the cellar, outward of the tie bar seat 5, locating the same at the crown of the arch, in the form of the box shown; and, in addition, we provide three depressed radial ribs, in the instance illustrated, one of which is marked with the reference letter *b* and the other two with the reference letter *c*. The strengthening rib *b* is the main one and it extends from the boss *a* outward and upward centrally in the curved forward end of the cellar and runs out or merges into the front wall of the box, directly under the mouth-lip or lifting beam *d*. The other two radial ribs *c* are located opposite to each other and extend from said boss *a* laterally outward and upward in the curved bottom of the cellar and run out or merge therein, before the curved bottom joins with the straight side wall of the cellar. When the cellar is pressed up from plate steel, by the usage of dies, as in the Randel box, the said depressed boss *a* and the radial ribs *b* and *c* are, of course, formed also by the usage of dies of the proper shape, and the metal will be of the same section or thickness as the other portions of the said cellar. If the cellar be a casting, the depressed boss *a* and radial ribs *b* and *c* will, of course, be cast integral with the other parts of the cellar and, nevertheless, can, if desired, be made hollow and of the same section or thickness as the other parts of the cellar. Whether formed in one or the other of said two ways, or however they may be formed, it will be seen that the boss *a* and the radial ribs *b* and *c*, disposed, as shown and described, greatly add to the strength of the cellar, near its forward end, without increase of its mass or weight; and with the forward end of the box made strong, in the ways above noted, the strains from the hoisting jack will be distributed to the best advantage for permitting the cellar to sustain such strains, without crush-

ing. In other words, when the hoisting jack is applied, with its movable head bearing against the boss *a*, the lifting strain will be transferred chiefly through the longitudinal radial rib *b* and the corners *e* to the cross beam *d* and be thereby first carried to the front end walls of the box and then delivered to the side walls of the box, about midway of their height. Of course, part of the strain is transferred by the radial rib *c* more directly to the said upper half portion and the side walls of the cellar. The intervening column or portions of the cellar wall, below the top, then receiving the strain so transferred, is relatively short, as compared with the entire depth of the cellar, and this short column is of sufficient strength to stand the strain and transmit the same to the top of the box.

If attempt had been made to use the vertical sides of the cellar, as a lifting column, for their full height, without any stiffening or strengthening, the sides would dish or buckle and the cellar crush, under the load. By combining with the specified features of strength, naturally present at the front end of the cellar, towit: the cross beam *d* and the corners *e*, the new features herein disclosed, towit: the boss *a* and the longitudinal rib *b*, and, if need be, the radial rib *c*, the problem was solved. By actual and extensive service, it has been found that our invention, herein disclosed and claimed, adapts such thin cellars to withstand successfully the jacking strains, even when the boxes are of the largest size and used under loaded cars of the largest capacity. It will, of course, be understood that for some sizes of boxes, the lateral radial rib *c* may be dispensed with, and that for still other and larger sized boxes, it may be desirable to add additional radial ribs. The essential things are the boss *a* and the longitudinal rib *b*, or its equivalent, getting its base of resistance in the boss *a*, and extending to a point under the mouth-lip or lifting beam *d*. It should also be noted that there is co-operation between the flat tie bar seat 5, formed on the bottom of the box, as described, and the features, above identified, added for jacking purposes, towit: the boss *a* and the radial ribs *b* and *c*. The said parts all coöperate to add strength to the bottom part of the cellar.

It will be understood that while the box illustrated is of arch-shape in cross section, and also longitudinally at its forward end portion, outward of the tie bar seat, and also of arch-shape in cross section, rearward of the tie bar seat, our invention would also apply to a box which was of rectangular form in cross and longitudinal sections.

What we claim is:—

1. A journal box cellar having a lower mouth-lip, adapted to serve as a lifting

beam, a jacking boss on its bottom, and strengthening means extending from said boss forward and upward to a point directly under said beam, substantially as described.

5 2. A journal box cellar having a lower mouth-lip, adapted to serve as a lifting beam, a jacking boss on its bottom, a strengthening rib extending from said boss forward and upward to a point directly under said beam, and additional strengthening means, in the bottom, coöperating with said boss and rib, substantially as described.

10 3. A journal box cellar having a lower mouth-lip, adapted to serve as a lifting beam, a jacking boss on its bottom, outward of its longitudinal center, a strengthening rib extending from said boss forward and upward to a point directly under said beam, and additional strengthening ribs extending radially from said boss in the bottom of the box, substantially as described.

15 4. A journal box cellar having a lower mouth-lip, adapted to serve as a lifting beam, a jacking boss on its bottom, outward of its longitudinal center, a strengthening rib extending from said boss forward and upward to a point directly under said beam, and two opposite radial strengthening ribs extending from said boss laterally outward across the bottom of the box, substantially as described.

20 5. A journal box cellar of arch-shape in cross section and also at its forward end below the lid opening, and having a mouth-lip,

adapted to serve as a lifting beam, a jacking boss at the crown of the bottom and three radial ribs extending therefrom, one forward and upward to a point under said beam and the other two laterally outward in the bottom of the box, substantially as described.

25 6. A journal box cellar having a rounded or arch-shaped bottom provided with a depressed jacking boss, at the crown of the arch, substantially as described.

7. A journal box cellar having a rounded or arch-shaped bottom provided with a depressed jacking boss, at the crown of the arch, outward of the tie bar seat, substantially as described.

30 8. A journal box cellar having a rounded bottom and provided with angular depressions on the opposite sides of its intermediate rounded portion, which depressions afford a flat bearing for the tie bar, the bottom of said cellar, outward of said angular depressions having a depressed boss and depressed ribs radiating therefrom, the one toward the outer end of the box and the other two toward the sides of the box, substantially as described.

In testimony whereof we affix our signatures in presence of two witnesses.
